[57] CLAIM

The ornamental design for a temperature controller, as shown.

DESCRIPTION

FIG. 1 is a front elevational view of a temperature controller showing our new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and

FIG. 7 is a right front perspective view thereof.

FIG. 1
